UNITED STATES PATENT OFFICE.

JOHN VLAHOS, OF RATON, NEW MEXICO.

PIPE-CLEANING MACHINE.

Application filed March 10, 1923. Serial No. 624,192.

To all whom it may concern:

Be it known that I, JOHN VLAHOS, a subject of the King of Greece, and a resident of Raton, in the county of Colfax and State of 5 New Mexico, have invented certain new and useful Improvements in Pipe-Cleaning Machines, of which the following is a specification.

This invention relates to a machine adapted for use in cleaning pipes, tubes, flues, etc., for removing rust or other deposits and also for polishing the exterior surfaces of the tubes.

An object of the invention is the provision 15 of a device for thoroughly removing or grinding off the formation of rust, dirt, scale, etc., in an efficient manner from the body of the pipe without injuriously affecting said body while under treatment.

20 A further object of the invention is the provision of a device which is simple and commercially practical because of its construction and its relatively light weight whereby the device may be readily transported to a boiler for cleaning the pipes of said boiler.

Other objects and advantages will become apparent during the course of the following description.

30 The invention is illustrated by way of example in the accompanying drawings, in which,

Figure 1 is a longitudinal elevation of the pipe cleaner.

35 Figure 2 is an end elevation of the same.

Figure 3 is a transverse vertical section taken along the line 3—3 of Figure 1.

Referring to the drawings, 1 designates a base member of a portable frame and which 40 is provided with spaced vertical standards 2 and 3. Mounted at its opposite ends in the standards 2 and 3 is a drive shaft 4 upon which is keyed a gear 5. A drum 6 is keyed to the shaft 4 and is of the same size and adjacent a drum 7 loosely mounted on the shaft. A belt 8 engages the drum 7 and idly revolves said drum when the machine 45 is not in operation.

In order to rotate the drum 6 and likewise 50 the shaft 4, the belt 8 is shifted to the drum 6 when desired.

A second shaft 9 is mounted at its opposite ends in bearings carried by the cross heads 10 and 11. The extreme ends of the shaft, as shown in Figure 3, project through 55 arcuately shaped slots 12 cut in the wall of the vertical standards 2 and 3, the radius of the arcuate slot being equal to the distance between the centers of the shafts 4 and 9.

Rigidly connected to each of the cross 60 heads 10 and 11 are a pair of guide rods 13, which have their upper ends slideable in passages formed in blocks 14 which are pivotally mounted on a rod 15, the ends of which being secured in openings in the vertical 65 standards 2 and 3 and adjacent the upper ends of the same. The rod 15 is located in substantially the same vertical plane passing through the shaft 9. The blocks 14 are similar in construction and shape to the 70 cross heads 10 and 11.

Coil springs 16 having their opposite ends abutting the inner faces of the blocks 14 and the cross heads 10 and 11 tend to maintain said cross heads at the lowermost position with the ends of the shaft 9 being located at the bottom of the arcuately shaped 75 slots 12.

Radial arms 17 and 18 are pivotally mounted adjacent the ends of the drive shaft 80 4 and loosely support the shaft 9 adjacent its end so that the shaft 9 may be bodily moved upwardly while the blocks 10 and 11 are forced against the springs 16 and the rods 13 will be moved through the passages in the block 14, the ends of the shaft 9 riding in the arcuately shaped slots 12.

Rigidly mounted on the shaft 9 are three 85 polishing wheels 19, 20 and 21 of steel or any other suitable material which are rotated through the intermeshing gears 5 and 10 and are adapted to have peripheral engagement with a flue pipe 22. Supporting the flue pipe 22 are a pair of series of rollers 23, 24, 25 and 23^a, 24^a, 25^a. These rollers 90 are rigidly connected to shafts that are mounted in bearings at the upper end of the vertical bearing blocks 26. As shown in Figures 2 and 3, each pair of rollers 23 and 23^a, 24 and 24^a, 25^a and 25 are spaced 95 sufficiently apart to support the pipe 22 with the rollers 19, 20 and 21 engaging said pipe.

Circular openings 27 are formed in the standards 2 and 3 through which the pipe 22 may be moved by the driving and driven rollers.

5 After the device has been set in position for cleaning the exterior surfaces of pipes, the belt 8 is applied to a source of power whereby the drum 7 is rotated and since this drum is loosely mounted on the shaft 4 10 said shaft will not be rotated until the belt 8 is slipped to the drum 6 by any well-known means. The shaft 4 is then rotated, likewise gear 5 and intermeshing gear 10 whence shaft 9 will be rotated together with the 15 wheels 19, 20 and 21. These wheels being in engagement with the flue pipe 22 will cause said pipe to be rotated and likewise the rollers 23, 24, 25 and 23^a, 24^a, 25^a. When any of the wheels 19, 20 and 21 meet an 20 enlargement or obstruction on the outer surface of the pipe 22 as the pipes are being moved between the various cleaning rollers the entire shaft including its operative connections, will be elevated against the tension of the spring 16 with the gearing 10 revolving around the gearing 5 and always in mesh with the same. It should be remembered that the gear 10 and shaft 9 are supported radially from the shaft 4 by the arms 30 17 and 18 so that the shaft 9 may be swung upwardly with all its parts.

The spring 16 maintains the shaft in its lowermost position with the end of said shaft seated in the lower ends of the arcuately shaped slots 12 whereby the wheels 19, 20 and 21 will be in their lowermost position for cleaning dirt or rust from the pipe 22.

Rollers 23, 24 and 25 which are adjacent the front end of the device have their 40 bearing blocks 26 connected together and movable as a unit by means of the screw 28 having an operating knob or handle 29. The screw passes through a threaded passage in the connection between said blocks 45 whereby said blocks are moved simultaneously and transversely of the frame for adjusting the rollers thus connected towards or away from the other series of rollers 23^a, 24^a and 25^a in making adjustments of the 50 spacing when larger or smaller pipes are cleaned. The connected blocks move in tracks 30.

The rollers 23^a, 24^a and 25^a have their 55 opposite faces inclined at an angle to the vertical whereby the pipe will be moved through the cleaning device.

What I claim is:

1. In a pipe cleaning machine, the combination of a frame, a drive shaft mounted 60 in said frame, a driven shaft, arms pivotally connecting the drive shaft with the driven shaft means operatively connecting the two shafts for simultaneous rotation, driving rollers on the driven shaft, and driven rollers spaced from each other and the driving

rollers for supporting the pipe for treatment, and means for maintaining the drive rollers in engagement with the pipe, said frame being provided with arcuate slots, the ends of the driven shaft being mounted in 70 said slots for movement, said driven shaft being movable about the drive shaft in the arc of a circle.

2. In a pipe cleaning machine, the combination of a frame having a base and two vertical standards, a drive shaft having its ends mounted for rotation on the standard, the standards being provided with arcuate slots, a driven shaft having its ends mounted for movement in the slots, arms pivotally mounted on the drive shaft at one end with their other ends connected with the driven shaft whereby the driven shaft is swingable through an arc with the drive shaft as the center, means operatively connecting the two shafts for simultaneous rotation, driving rollers on the driven shaft and driven rollers spaced from each other and the drive rollers for supporting a pipe for treatment, and resilient means for maintaining the driving rollers in engagement with the pipe and the 80 ends of the driven shaft at the bottom of the arcuate slots.

3. In a pipe cleaning machine, the combination of a frame having a base and two vertical standards, a drive shaft having its ends mounted for rotation on the standard, the standards being provided with arcuate slots, a driven shaft having its ends mounted for movement in the slots, arms pivotally mounted on the drive shaft at one end with their other ends connected with the driven shaft whereby the driven shaft is swingable through an arc with the drive shaft as the center, means operatively connecting the two shafts for simultaneous rotation, driving rollers on the driven shaft and driven rollers spaced from each other and the drive rollers for supporting a pipe for treatment, 90 a rod having its ends secured to the vertical standards and spaced above the driven shaft, spaced blocks pivotally mounted adjacent the ends of the rod and provided with spaced vertical passages, cross heads pivotally mounted adjacent the ends of the driven shaft, spaced rods secured to the cross heads and slidably in passages in the block, 100 springs on the rod and between a block and a cross head for forcing the cross head downwardly and likewise the driven shaft in its lowermost position.

4. In a pipe cleaning machine, the combination of a frame, a drive shaft mounted for rotation in the frame, a driven shaft mounted for rotation and bodily movement in an arc of a circle in said frame, means operatively connecting the two shafts for simultaneous rotation, driving rollers on the driven shaft, and driven rollers spaced from each other and the drive rollers for 110 120 130

supporting a pipe for treatment, a rod rigidly mounted in the frame, said blocks pivotally mounted on the opposite ends of the rod and provided with spaced vertical passages, cross heads pivotally mounted on the opposite ends of the driven shaft, spaced rods secured to the cross head and slidable

in passages in the blocks, springs on the rod and between the blocks and the cross heads forcing the cross heads downwardly and ¹⁰ likewise the driven shaft for maintaining the driving rollers in engagement with the pipe which is being treated.

JOHN VLAHOS.
